United States Patent Office

Des. 189,491
Patented Dec. 27, 1960

189,491

LINK FOR AN EXPANSIBLE BRACELET OR SIMILAR ARTICLE

Nathan Goodman, Forest Hills, N.Y., assignor to Baldwin Bracelet Corporation, New York, N.Y., a corporation of New York

Filed Aug. 27, 1959, Ser. No. 57,335

Term of patent 7 years

(Cl. D45—4)

Fig. 1.

Fig. 2.

Fig. 3.

Fig. 4.

Figs. 1 and 2 are respectively an enlarged top plan view and a side elevational view, on an enlarged scale, of one of the links embodying my new design;

Fig. 3 is a sectional view taken on line 3—3 of Fig. 1; and

Fig. 4 is a perspective view of one of the links.

I claim:

The ornamental design for a link for an expansible bracelet or similar article, substantially as shown.
